(57) **CLAIM**

The ornamental design for an electric toothbrush replacement head, as shown and described.

DESCRIPTION

FIG. 1 is a front, left and top perspective view of an electric toothbrush replacement head, showing my new design; FIG. 2 is a rear, right and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines in the figures depict portions of the electric toothbrush replacement head that form no part of the claimed design.

1 Claim, 8 Drawing Sheets
